CONTAINER CLOSURE APPLYING
APPARATUSArthur I. Risser, Chicago, Ill., assignor to U. S.
Bottlers Machinery Co., Chicago, Ill., a corpo-
ration of Illinois

Application December 31, 1934, Serial No. 759,930

20 Claims. (Cl. 226—88)

This invention relates to container closure applying apparatus or machines, and more particularly pertains to such apparatus for applying screw caps to containers.

5 An object of the invention is to provide such a machine that will be compact, durable and efficient, and wherein the capping of containers is accomplished expeditiously.

Another object of the invention is to provide 10 such a machine with more efficient means for feeding caps to the capping mechanism of the machine without causing the disfigurement or marring of the caps.

Another object of the invention is to provide 15 such a machine wherein the aforesaid objects are attained with the fewest number of operating parts.

The attainment of the foregoing objects is 20 accomplished by certain improvements and organizations of elements or parts, as will be hereinafter more fully described, and, upon reference thereto, other objects and advantages as well as certain novel features will become apparent, which novel features are defined in the 25 claims.

In the drawings:

Figure 1 is a front view of the machine, with 30 certain parts broken away and parts in section to disclose parts otherwise hidden.

Figure 2 is a detail plan section taken on the section line 2—2 of Figure 1.

Figure 3 is a plan section taken on the section line 3—3 of Figure 1.

Figure 4 is a vertical detail section of the 35 machine with parts broken away, as taken substantially on the section line 4—4 of Figure 3.

Figure 5 is a detail plan section taken on the section line 5—5 of Figure 1.

Figure 6 is a vertical section of the machine, 40 as taken substantially on the section line 6—6 of Figure 1 with parts broken away and other parts omitted to clearly disclose more important parts.

Figure 7 is a view similar to Figure 3, in 45 enlarged scale with parts in section and parts broken away to disclose parts otherwise hidden, and showing certain operating parts in changed position.

50 Figures 8 and 9, on the separate sheets, when taken together with the division lines 8^a and 9^a of the figures, respectively understood as matching, so that the parts above and below said lines respectively match, form a detail vertical central section of the machine as taken substantially on

the section line 8—9 of Figure 7 with parts broken away and parts omitted.

Figure 10 is a plan section of the machine as 5 may be understood as taken substantially on the section line 10—10 of Figure 8, with parts in changed position, parts omitted and parts broken away.

Figure 11 is a detail section taken substantially on the section line 11—11 of Figure 10.

Figure 12 is an enlarged detail section taken 10 on the section line 12—12 of Figure 3.

Figure 13 is a detail section taken on the section line 13—13 of Figure 12.

Figure 14 is a detail section taken substantially on the section line 14—14 of Figure 3 with 15 parts broken away.

Figure 15 is an enlarged detail section of a portion of certain capping apparatus, as illustrated in full lines in Figure 6, or the view may be said to be taken substantially on the section 20 line 15—15 of Figure 1.

Figure 16 is a vertical detail section of Figure 15 taken substantially on the section line 16—16 of said figure with parts shown in changed position.

Figure 17 is a plan section of Figure 15 as taken 25 on the section line 17—17 of said figure.

Figure 18 is a bottom view of the structure 30 shown in Figure 15, with certain parts broken away.

Figure 19 is a view similar to Figure 18 showing parts in changed position, the view comprising a bottom view of the structure of Figure 16.

Figure 20 is a detail plan section of Figure 8, as taken substantially on the section line 20—20 35 of said figure.

Figure 21 is a detail vertical section of Figure 8, as taken substantially on the section line 21—21 of said figure.

The structure illustrated, forming one embodiment of the invention, includes a supporting frame or base in the form of a hollow upright circular pedestal 1 having a centrally open cover 2 suitably secured thereon upon which is supported, in spaced relation thereabove and coaxial therewith, a container support or table in the form of a substantially circular shelf 3 secured to the cover by posts 4.

The containers or bottles 5 to be capped are placed on a container feeding conveyor 6 in the 50 form of an endless link-belt of the cleated sprocket chain type, whose upper stretch moves toward and is in the plane of the top surface of the shelf 3 which is cut away, as at 7, to accommodate said upper stretch. Each container is then conveyed 55

by the belt into cooperative relation with transporting means which transports same over the shelf in an arcuate path about the axis of the pedestal, during which time the container is capped by one of two capping devices or heads 8 disposed above the shelf. On continued movement of the container during transport, after being capped, it is deflected onto a container receiving conveyor 10 in the form of a link belt similar to the conveyor 6, and whose upper stretch is in the plane of the shelf which is cut away, as as 11, to accommodate same, whereupon the capped containers are carried away from the machine.

15 The conveyors 6 and 10 are arranged respectively along the front and rear of the machine, and extending horizontally under the shelf to one side of the axis of the pedestal is a shaft 12 on which are sprockets 13 and 14 over which are received the conveyors 6 and 10 respectively, to be driven in unison. The shaft is mounted rotatably centrally in spaced bearings 15 of a bracket structure 16 secured to the base.

20 The conveyor belts 6 and 10 extend from their driving sprockets to the left and right of the base, respectively, and the upper stretch of each belt is supported upon a horizontal guide structure 16^a, mounted on a bracket 16^b on the base, and upon which is mounted guide rails 16^c above 25 the belt between which the containers are guided thereon. In that the outer end of each guide structure is not shown, it will be understood that on said outer end is provided an idler sprocket or other well known means for supporting the outer 30 end of each belt.

25 For driving the conveyor shaft 12, as well as other mechanism, later described, a main vertical drive shaft 17 is disposed at rear of the machine, whose lower portion is rotatably mounted in a bearing 18 of a bracket 19 on the base 1, and whose upper portion extends considerably 35 upward to be rotatably received in a bearing 20 of a bracket member 21 secured on the top end of a stationary vertical column 22 in the form 40 of a hollow shaft extending centrally upward of the base 1 which has a central bearing 23 in which the lower end of the column is secured. The drive shaft 17 is in driven connection with a main drive shaft 24, through the intermediation 45 of a suitable speed reducing device 25 mounted on the base 1, and from which device the shaft 24 extends, and which device is in suitable connection with the shaft 17 through a common clutch device 26 controlled by lever mechanism 50 55 27 mounted on the base. The drive shaft 17 drives the conveyor shaft 12 through suitable gearing 28 arranged in a housing 29 on the base 1.

60 The container transporting means includes a container positioning member 30 in the form of a cam wheel disposed above the shelf 3 and rotatably mounted on the central column 22, surrounding which is a sleeve 31 extending through an aperture in the shelf and on the top end of which is secured the hub 32 of the wheel. The 65 cam wheel 30 has opposite container positioning pockets 33, which, upon counter clockwise rotation of the wheel as seen in plan, are alternately brought into cooperative relation with containers being conveyed into the machine on the conveyor 70 6 to receive the containers. Upon being received in a pocket a container is held herein so as to be held from rotation, during application of a screw cap, by container engaging means or a clamping device 34 which is caused to travel with the wheel 75 during about one quarter of its revolution upon

receiving a container, whereupon the device is operated to release the container, from which point it is deflected by a deflecting member 35 onto the receiving conveyor. The cam wheel is continuously rotated by the drive shaft 17 through intermediation of a spur gear 36 secured to the gear 37 mounted on the bottom end of the sleeve 31 within the top of the pedestal 1, and which gear 36 is in mesh with a spur gear 38 on the drive shaft 17. Secured to the gear 37 is a 10 cover 37^a which overlaps the cover 2 of the pedestal for enclosing the gears.

15 The container engaging or gripping means includes a head 39 in the form of an elongated block disposed in the plane of the cam wheel and guided to oscillate approximately 90° about the axis of the column 22 by means of an arcuately formed guide or cam 40 mounted at one end upon the bracket 16 on the side of the base and at its other end on a similar bracket 16^d on the front 20 of the base, and which cam has inwardly projecting upper and lower track portions 41 and 42 oppositely recessed to provide guideways within which are received, to be guided, rollers 43 rotatably mounted above and below the block 39 on 25 pins 43^a at both ends thereof. As best seen in Figures 12, 13 and 14, disposed inward of the block 39 and mounted adjustable toward and away from the axis of the machine is a container engaging member or jaw 44 in the form of a flat 30 block, having secured to its outer face a friction member 45 of resilient material, such as leather or rubber, for engaging so as to hold a container in a pocket of the cam wheel. The engaging member 45 is resiliently supported on the head 35 39 through intermediation of an intermediate carrier block 46 recessed in its outer face, as at 47, to receive, guided therein, said member. To further support the jaw on the carrier, the jaw has two pins 48 slidably received in the carrier 40 and whose heads 49 limit outward movement of the jaw by engaging shoulders 50 in the carrier.

45 The jaw is resiliently urged outward by means of compression springs 51 interposed between the jaw and carrier which are recessed to receive the 45 springs. The carrier is supported on the head 39 so as to be adjustable toward and away from the container positioning member or cam to accommodate various sizes of containers, by means of two guide rods 52 extending from the carrier 50 and which are slidably received in the head. Extending threaded through the head between the rods 52 is an adjusting screw 53 for adjusting the carrier and whose enlarged inner end portion 54 is confined for rotation in a recess in the 55 carrier, by a plate 55 mounted on the carrier through which the screw passes.

60 As best seen in Figures 3, 7 and 10, the recessed portions of the track member 40 are concentric with the axis of rotation of the cam wheel, intermediate its ends within an arc of about 60°, as indicated at B, Figure 7, and continuing from said arcuate portions toward each end tangentially of the arc outward of the machine axis, as at C and D, Figure 7. Thus, referring to Figure 65 3, when the head 39 is in its starting position opposite a pocket of the cam wheel when same is in cooperative relation to receive a container from the feed conveyor, the head is guided on the tangential portion C of the track portions 41-42 70 whereby it is caused to cant outward of the track, whereupon the head is retracted slightly, causing the retraction of the jaw so that the friction face thereof is disposed at such an angle to the incoming container on the conveyor 6 as to effect 75

camming same into the pocket of the cam wheel.

Upon said positioning of a container in the cam wheel pocket, the head 39 is caused to travel with the wheel upon the concentric portions of the track 40 whereupon it is urged inwardly causing the jaw to resiliently but firmly hold the container in the cam wheel pocket to prevent its turning during the capping operation (see Figure 7). On continued movement of the head with the cam wheel, to its final position, after having traveled about 90°, as seen in Figure 10, the head is then disposed upon the tangential portions D of the track 40, whereupon it is again canted outward to cause the retraction of the jaw from pressure engagement with the container to permit same to be deflected onto the receiving conveyor on continued rotation of the cam wheel. The head is then returned to its starting position to cooperate with the opposite pocket of the cam wheel.

The head 39 is oscillated upon the track 40 in timed relation with the cam wheel by an actuator such as a bell crank arm 56 whose hub portion 57 is pivotally mounted on the sleeve 31 below the shelf 3. The actuator arm has an arm portion 58 extending from its hub over the cover 2 of the base 1 and continuing into an upright portion 59 projecting beyond the edge of the shelf 3 and having an upstanding pin 60 received within a guide groove 61 in the bottom of the head 39 and extending radially of the machine axis, to permit radial movement of the head upon oscillation of the arm 56. The arm is oscillated twice upon a complete revolution of the cam wheel so that the head 39 alternately cooperates with the pockets 33 of the cam wheel. To this end, the gear device 37 with its cover 37a has slidably mounted therein, on opposite sides of the axis thereof, two vertical pins 62 which extend therethrough, the pins being raised to engage the arm portion 58 of the arm 56 in effecting its connection with the gear device 37 to cause same to move therewith in causing the clamping head 39 to move with the cam wheel, by a stationary arcuate cam 63 mounted on the base 1. (See Figures 8, 10 and 11.) Upon the arm 56 reaching its intermediate position, the pin 62 driving same is lowered out of contact therewith by two cams 64 mounted on the base and which engage on opposite sides of the enlarged head 65 at the bottom end of each pin. After said disengagement of the pin the arm is caused to move with the cam wheel by the clamping engagement of the jaw with the container positioned in a pocket of the wheel.

For retracting the actuator arm 56, the arm has an arm portion 66 on whose end is pivotally connected a link arm 67 having a hook portion 68 on its free end adapted to be engaged by a pin 69, depending from a disc 70 on the drive shaft 17, when same is rotating outward of the machine, thus causing the retraction of the arm. (See Figures 3, 4, 7 and 10.) As the pin 69 starts to rotate inward toward the machine it disengages the hook, which is caused to return to its initial position for engagement with the pin by the movement of the actuator arm with the cam wheel. For maintaining the hook 68 of the link arm in the path of the pin 69, it is caused to move in an arcuate path about the axis of the drive shaft by a stationary arcuate cam 71 within whose arcuate cam groove 72 is guided a roller 73 centrally mounted on, so as to depend from, the link arm, the cam being secured at its ends 75 on the base cover 2, as at 74-74.

The capping heads 8 and cooperating mechanism will now be described. Surrounding the central column 22, and spaced above the cam wheel 30, is a capping device mounting sleeve 75, connected so as to be normally stationary but vertically adjustable on the column by means of an adjusting screw shaft 76 centrally disposed on the column on which is a nut 77 having opposite wings 78 passing through elongated slots 79 in opposite sides of the column and being secured in opposite slots 80 on the top of the sleeve by a ring nut 81 threaded onto the top end of the sleeve. The screw shaft passes through a bearing 82 at the bottom of the column and rests upon a thrust bearing 83 mounted on the base. The screw shaft is operated by a hand crank 84 mounted on a horizontal shaft 85 rotatably mounted on a bearing 86 in the base and on the end of the shaft 86 is a bevel gear 87 in mesh with a bevel gear 88 on the bottom end of the screw shaft.

Rotatably mounted on the supporting sleeve 75 is a capping device supporting member 89 in the form of a gear through which are reciprocably mounted in vertical bearings 90, on opposite sides of its axis, two hollow spindles 91, at the bottom ends of which are mounted the capping devices 8. The spindles are arranged so as to be coaxial above the container positioning pockets of the cam wheel 30 and are rotated with the wheel by means of the gear 89 being in driven connection with a spur gear 92 on the drive shaft 17. The gear 92 is maintained in the plane of the gear upon adjustment of the heads with the carrier sleeve, by means of a gear casing 93 secured on the top end of the sleeve 75 around which is secured a depending sleeve portion 94 of the top wall portion 95 of the casing. The shaft 17 extends through the gear casing 93 within a sleeve 96 depending from the bottom wall portion 96' of the casing and at the bottom end of which sleeve are opposed pins 97 received within the peripheral groove 98 in the hub 99 of the gear 92. The gear 92 is maintained in driven connection with the shaft 17 by means of suitable key connection with the elongated keyway 100 in the shaft. The spindles are continuously rotated for applying screw caps on the containers, during transport from the feed conveyor to the receiving conveyor, by means of a spur gear 101 mounted rotatably on the carrier sleeve 75, and which is in mesh with a smaller spur gear 102 in slidable key connection on each spindle. The gear 102 of each spindle is maintained in the plane of the gear 101 by being confined rotatably between the bearing 90 and a bearing block 103 mounted on the gear 101 and through which the spindle also passes. The gear 101 is driven for rotating the spindles, by the drive shaft 17 on which is a spur gear 104 confined rotatably in the casing 93 and in suitable key connection with the keyway 100 of the shaft. The gear 104 is in gear connection with a spur gear 105 secured on the top end of a sleeve 106 extending from the hub portion 107 of the gear 101, through the intermediation of suitable speed and direction controlling gearing 108 mounted within the casing 93.

Generally, each spindle is caused to be lowered in bringing its capping device into cooperative relation over a container upon same being positioned in a pocket of the cam wheel, in which position the device remains during transport of the container over the shelf, then the device is raised off the container upon application of the cap, whereupon it is again lowered slightly into 75

cooperative relation with a cap feeder means 109 for receiving a cap preparatory to another operation.

Each spindle is operated to be raised positively 5 and resiliently lowered through intermediation of an operator head 110 carried on the spindle which projects through a bearing portion 110^a in the head. The head 110 is carried on the spindle so as to be resiliently compressible thereon, by means 10 of its spring pressed engagement with the under side of the collar 110^b fixed on the spindle. The operator head is spring pressed against the collar by means of a compression spring 110^c surrounding 15 the spindle and interposed between a washer 110^d under the head and the top of the capping head on the spindle.

On each carrier head are guide rods 111 extending upward on opposite sides of the spindle to be reciprocably mounted and projecting through 20 the gear 89, the bearing portion 90 and the block 103 of the gear whereby the carrier head is held non-rotatable with respect to the gear 89. The carrier heads of the spindles are raised and lowered for operating the spindles, by a drum shaped 25 cam 112 secured stationary on the lower end of the carrier sleeve 75, and which cam is connected to operate the carrier heads by means of a roller 113 mounted on each head being received within the peripheral cam groove 114 in the cam.

30 Referring to Figures 15 to 19 particularly, each capping head includes a hollow chuck head 115 disposed at the end of its respective spindle coaxial therewith and being frictionally connected thereto by means of a friction clutch device 116. 35 To this end the chuck head has secured to its top end a sleeve 117 within which is rotatably mounted the lower end of the spindle by means of a ring nut 118 threaded into the top end of the sleeve and a ball bearing 119 confined between the ring nut and a peripheral flange 120 on the lower end of the spindle. The clutch head sleeve is frictionally connected to rotate resiliently with the spindle by means of a cupped shaped collar 121 which is slidably keyed, as at 122, with the 40 bottom end of the spindle, and which surrounds the clutch sleeve 117 with an annularly flanged bottom 123 for pressure engagement with a friction ring 124, of such material as leather, which is maintained on the peripheral central flange 125 of the clutch sleeve. The cupped collar 121 is maintained in pressure engagement with the friction ring 124 by means of a coiled compression spring 126 surrounding the collar and interposed 45 between its flanged end and the inner top flange 127 of a housing sleeve 128 threaded onto the peripheral flange 125 of the clutch sleeve 117.

The chuck head has an enlarged hollow concentric bottom end 115^a within which is mounted a screw cap chuck 130 including a plurality of annularly arranged closely adjacent cap gripping members such as jaws 131, whose inner surfaces 132 are of cylindrical formation so as to snugly surround a screw cap 133 whose skirt is of cylindrical form. The jaws are carried on a chuck 60 bottom portion 134 comprising a cylindrical head reciprocably mounted in the chuck head bore portion 135, and having a peripheral flange 136 received within a groove 137 in the inner side of each jaw, whereby the jaws are carried on the 65 bottom portion so as to be movable to expanded and contracted relations with respect to each other respectively loosely but snugly receiving and gripping a cap. The jaws are contracted for gripping a cap on the downward movement of the 70 bottom portion, by a ring cam 138 mounted within

the chuck head portion 115^a so as to surround the jaws and having a downwardly converging conical inner cam surface 139 with which the outer surface 140 of each jaw is correlative formed. The bottom portion is operated by an operator stem or pin 141 resiliently connected therewith, which is reciprocably mounted in the upper reduced portion 142 of the chuck head, and being limited for reciprocation by means of a cross pin 143 extending therethrough and projecting through opposite slots 143^a in the reduced portion. The pin 141 is resiliently connected with the bottom portion to cause the jaws to resiliently grip a cap on the downward movement of the pin upon being operated by means later described. To this end, the pin 141 extends down into the bore 144 of the bottom portion with an enlarged bottom end 144^a held resiliently against the shoulder 144^b in said bore by means of a compression spring 144^c confined between said enlarged end and a plug 144^d 20 threaded into the bottom end of the bottom portion bore.

Means is provided on each capping head for picking up a cap when the head is in cooperative relation with the cap feeding means, and supporting same loosely but snugly centrally confined within the jaws of the head during its movement from the feeding means to a container on the conveyor 6, and until the threaded neck of the container slightly projects into the cap. The means 30 includes a group of resilient members 145, in the form of fingers, preferably four, arranged about the chuck head, with which head they are in cooperative pivotal connection, and having inturned bottom portions 146 extending under the chuck 35 head to terminate in tapered ends 147 whose top tapered surfaces 148 cooperate to provide a tapered seat for the edge of a cap confined in the chuck, whereby the cap is centered therein.

The fingers are carried on the chuck head so as to be rotatable therearound and reciprocable as a group with respect thereto, which reciprocable movement of the fingers is controlled by the pin 141 so as to cause the cap supported on the inward extensions of the fingers to move down with the 40 jaws upon application thereof. To this end, the fingers extend upward from their bottom portions about the enlarged lower end 115^a of the chuck head, then continue angularly inward to extend through radial slots 150 of a finger carrier in the 45 form of a disc collar 151 on which the fingers are pivotally mounted on pins 152 projecting through the depending side wall portions 153 of the slots. The disc collar 151 is mounted reciprocably and rotatably upon the reduced upper portion 142 of the 50 chuck head, by means of a split collar 154 slidably received on the reduced portion and on which split collar the disc collar is rotatably mounted so as to rest upon the lateral shoulder or flange 155 thereof. Surrounding the reduced upper portion 142 of the chuck head 115, is a compression spring 155^a which is interposed between the split collar flange 155 and the shoulder 156 of the chuck head for resiliently holding the chuck 130 and the resilient fingers in raised position in relation to 55 the chuck head. The chuck is thus held in raised position by reason of the lateral pin 143, of the chuck operating pin 141, being extended to engage in recesses 157 in the top edge of the opposite halves of the split collar, whereupon the pin 143 is held by action of the spring 155^a, against the top end of slots 143^a in the chuck head.

Referring to Figure 16, it will be seen that when the chuck operating pin 141 is moved downward, in lowering the jaws so as to cause the operation 75

thereof, the fingers are moved downward in unison therewith through intermediation of the pin 143 and the split collar 154.

For resiliently urging the fingers inward, an endless coiled tension spring 158 surrounds the fingers below their pivots, and each finger having a recess 159 for receiving the spring, the fingers being limited for inward movement, so that their tapered ends project slightly under a cap, by engagement with the side of the chuck head.

For protection from possible damage, the fingers are surrounded by a housing 160 in the form of a sleeve of thin metal which is mounted on so as to depend from the disc collar 151.

Referring to Figures 1, 3 and 6, it will be seen that when a container has been received within a pocket of the cam wheel 30 the capping head thereover has been lowered by the cam track portion 161 of the cam 112, until the cap 133 in the chuck, fed therein by means later described, is disposed over the container neck 163 so that the neck slightly enters the cap. (See Figure 15). At this point the chuck 130 is caused to grip the cap, by lowering of the pin 141, which chuck, on continued movement of the head with the cam wheel, and downward movement of the capping head to the lower cam track portion 164 of the cam 112, screws the cap down on the container. (See Figure 16). The completion of the capping operation of the head occurs when the container thereunder reaches a position just prior to being released by the clamping device 34, whereupon the chuck 130 is released from the cap by raising of the pin 141, and the capping head is then raised by the cam track portion 165 of the cam 112, to its uppermost position, in which position it is shortly held by the cam track portion 166 of said cam. The capping head is then lowered slightly by the cam track portion 167 of the cam 112 to be brought into cooperative relation with the cap feed device 109, later described, then raised again to a position just below its uppermost position, controlled by the cam track portion 168, of said cam, until it is again lowered upon a container by the action of the cam track portion 161 of the cam.

For operating the pin 141 to cause the application of the chuck 130 to grip and release a cap in the chuck during said movement of its respective capping head upon a container, a rod 169 is slidably mounted within each spindle, and whose lower end is in contact with the top end of the pin 141 in the chuck head, and whose upper end is in cooperative connection with an operating device 170, on each spindle, for depressing the rod to cause the operation of the pin 141. The device 170 includes a bearing member 171 mounted on the top end of each spindle, and confined between two collars 172 on the spindle so that the spindle may rotate in the bearing. The bearing has a lug extension 173 through which the reduced end portion 174 of one of the guide rods 111 of the carrier head 110 extends to maintain the bearing non-rotatable with respect to the carrier head. On the reduced end portion of the guide rod extension 174 is pivotally mounted a bell-crank lever 175 within whose forked bearing portion 176 the lug 173 of the bearing 171 is received to cause the lever to be raised and lowered with the spindle.

The bell crank lever 175 has an arm portion 177 extending over the top end of the rod in which is mounted a ball bearing member 178 engaging a cam 179 on the arm portion for operating the rod upon oscillation of the bell crank.

The bell crank lever 175 is oscillated at the proper time to cause the application and release of the chuck 130 upon the orbital movement of its capping head, by means of a cam 180 in the form of a drum mounted on the depending sleeve extension 181 of the lower portion of the gear casing which surrounds the gear hub extension 170. The other arm portion 182 of the bell crank has a roller 183 maintained in operative engagement with the periphery of the cam by a tension spring 184 connecting between said arm portion and the bearing 171.

In the event a cap has not been applied during the capping operation of either head, due to the absence of a container thereunder, the cap 15 is released from the chuck by operation of the resilient fingers upon the head reaching its uppermost position during its orbital movement, so as to clear the chuck for the reception of another cap from the cap feeding means 109. To accomplish this, the means associated with each capping head includes a cam-collar 186 reciprocably mounted on the sleeve extension 117 below its flange 125. The cam-collar has a lower internal conical cam surface 187 for engagement with the upper end projections 188 of the fingers 145 when lowered for contracting same in causing the expansion of the lower portions 146 thereof in releasing the cap.

The cam collar is operated by a yoke 190 disposed thereabout on which are opposite pins 191 engaged in the peripheral groove 192 in the collar, which yoke has two upright guide rods 193 extending upward through, so as to be reciprocable, in the carrier head 110 of each capping head, and on the top end of which rods are mounted a cross piece 194 for engagement with a tension spring 195 interposed between the cross piece and the carrier head for resiliently holding the cam collar 186 in raised position against the shoulder 196 of the sleeve 117. Referring particularly to Figure 6, it will be seen that when a capping head is in its uppermost position during its orbital movement, controlled by the cam track portion 166 of the cam 112, the upper ends 40 of the guide rods 193 are engaged with the lower surface portion of the supporting gear 89, thus holding the cam collar 186 depressed for causing the operation of the fingers 145 to release a cap.

The cap feeding means 109 will now be described. Referring to Figures 3, 4, 6, 7, 8 and 9, with particular reference to Figure 8, when one of the capping heads 8 is in its lowermost position, during the capping operation thereof, the opposite capping head 8, is caused to be lowered slightly by the cam depression 167, of the cam 112, into cooperative relation with the cap feeding means to receive a cap, as briefly mentioned in the foregoing. The cap feeding means includes a horizontally rotating cap feeder head 200 in the form of a disc, depending from whose centrally recessed housing portion 201 is a hub 202 for mounting upon the top end of a rotating hollow shaft 203 vertically disposed alongside the shelf 3, and mounted, so as to be vertically adjustable, in an elongated bearing 204 of a bracket 205 secured to the base 1. On opposite sides of the axis of the disc are disposed radial slides 206 in the form of short rods reciprocably mounted 60 in guideways or radial bores 207, in the disc, which extend from the housing portion 201 thereof. Each guideway 207 opens into a narrow slot 65 in the top of the disc 200 through which projects an upstanding cap carrier in the form of an up- 70

right pin 208 having an enlarged head 209 upon which is adapted to be placed a threaded cap by cap supply means 210, later described, upon rotation of the feeder head. As the feeder head 5 200 is rotated in the opposite direction to the direction of orbital movement of the capping heads, each slide 206 is actuated by a cam 211, mounted stationary within the disc housing portion 201, for causing its respective cap carrier 10 pin 208 to move with a capping head coaxial therewith, during a given interval of its orbital movement about the axis of the column 22, so that the cap holding fingers 145 of the capping head will ride over the cap on the pin in maintained axial alignment upon lowering of the head 15 thereover to insure engagement of the fingers under the edge of the cap, and thus cause same to be held in the chuck of the head upon being raised off the carrier pin. Said movement of 20 each cap carrier pin as controlled by the cam 211 is indicated in dot and dash lines F in Figure 7, the portion F' of the said dot and dash lines indicating the path of the cap carrier in its movement about the axis of the center column 25 22 so as to be maintained in coaxial alignment with a capping head during its engagement therewith in the feeding of a cap thereto.

The cam 211 is in the form of a disc disposed in the housing portion 201 of the feeder head 30 200, and having a cam groove 212 within which is received a roller 212^a secured on the inner end of each slide 206. The cam is mounted fixedly on the top end of a stationary shaft 213 extending through the feeder head shaft 203 and being 35 secured at its bottom in a cross head 214 which also forms an end support for the feeder head shaft 203.

The cap feeder head 200 is rotated in unison with, but in opposite direction to, the orbital 40 movement of the capping heads by means of a spur gear 214^a mounted on the shaft 203 of the cap feeder head, in sliding key connection therewith, and meshing with the spur gear 37 of like size provided on the sleeve 31 of the cam wheel 45 30. The gear 214^a is maintained in the plane of the gear 37 by being confined between the bearing 204 of the bracket 205 and a bearing 214^b mounted on the extension 214^c of the bracket 205.

The cross head 214 is reciprocably mounted 50 upon two guide rods 215 depending from the bracket 205 on opposite sides of the shaft 203, and being connected at their bottom ends by a cross piece 216. The cross head is actuated to raise or lower the feeder head 200 in adjusting 55 same upon adjustment of the capping heads, by operable connection with the adjusting screw 76. To this end, as best seen in Figures 1 and 4, the cross head has a lateral extension 216 with a threaded vertical bearing 217 in threaded engagement with a vertical adjusting screw 218 whose top end is rotatably mounted in a bearing 219 of the bracket 205, and whose lower end is rotatably mounted on a bearing 220 on the base 1. The adjusting screw 218 is rotated for raising or 60 65 lowering the cap feeder head in unison with similar adjustment of the capping heads, by means of suitable gearing 221 operably connecting the bevel gear 88 of the screw 76 with the adjusting screw 218.

70 There are many types of cap supplying devices which may be employed for supplying caps to the pins 208 of the feeder head 200, instead of the form herein disclosed. The form illustrated includes a magazine 222, within which the screw 75 caps are guided in uniform edgewise single order,

and has an upright upper portion 223 continuing downward into an angular bottom end portion 224, inclining downward over the path of the pins 208.

The end cap in the magazine is resiliently held in the bottom end, and, is disposed angularly so that its open side is in the path of a head of a pin 208 to be engaged thereby and carried positioned thereon from the magazine.

The means shown for resiliently holding the 10 end cap in the magazine includes two spring fingers 225 secured on opposite sides of the magazine and having padded ends beyond the end to engage on opposite sides of the cap. The bottom wall 226 of the magazine bottom end is recessed inward of the end, as at 227, to enable passage of the head of a cap carrier pin into the end cap to be fed thereon. The top side 228 of the magazine continues beyond the bottom end into a horizontal tongue extension 229 under 20 which the end cap rides upon being carried on a carrier pin from the magazine, whereby the cap is positively centered on the pin.

The magazine is mounted on a bracket 230 secured to an upright 231 mounted vertically adjustable in a pedestal 232.

The magazine may extend upward to a sufficient height for accommodating a considerable supply of caps, or cap sorting and feeder means may be employed in association with the magazine for maintaining a supply of caps properly positioned therein, such as disclosed in my Patent No. 1,775,141 of September 9, 1930, assigned to the U. S. Bottlers Machinery Company, Inc.

Certain structure relating to the cap applying 30 chuck in connection with which the present invention forms one embodiment, forms part of the subject matter of my copending application, Ser. No. 704,619, filed December 30, 1933, in which application said structure is broadly disclosed and 40 claimed.

Certain structure relating to the container transporting means forms the subject matter of my copending application, Ser. No. 20,208, filed May 7, 1935, in which said structure is broadly 45 disclosed and claimed.

What I claim is:

1. In a screw capping machine, means for placing a screw cap over a container having a threaded open end whereby one partially enters the other loosely and centrally therewith, and means operative upon said placing of the cap for screwing same down onto the container, wherein the first mentioned means includes a group of resilient members having portions formed to loosely support the cap about the bottom edge thereof so as to centrally locate same with a container, said members having portions formed for cooperating with the top edge of a cap in effecting movement of the members in permitting entry of the cap between the members in positioning same upon said support portions, and means for causing relative movement of the cap and members to cause said entry of the cap.

2. In a screw capping machine, means for placing a screw cap over a container having a threaded open end whereby one partially enters the other loosely and centrally therewith, and means operative upon said placing of the cap for screwing same down onto the container, wherein the first mentioned means includes a group of angularly arranged pivotally mounted, depending fingers having inturned bottom portions with ends tapered to support the cap about its bottom.

edge and means for resiliently urging the fingers inward.

3. In a screw capping machine, means for placing a screw cap over a container having a threaded open end whereby one partially enters the other loosely and centrally therewith, and means operative upon said placing of the cap for screwing same down onto the container, wherein the first mentioned means includes a group of annularly arranged pivotally mounted depending fingers having inturned bottom portions, said bottom portions having inner ends provided with upper and lower converging cap engaging surfaces upon the upper of which the cap is adapted to be supported, and the lower of which surfaces is adapted for camming engagement with the top edge of the cap in spreading the fingers to permit entry of the cap therebetween in the feeding of same to the upper surfaces, and means for relatively moving a cap and said fingers to feed the cap between the fingers.

4. The combination with a machine of the class described for applying threaded caps having cap feeding means and a cap applying chuck including contractable cap gripping means arranged normally to freely receive a cap therein and being movable into and out of cooperative relation with the feeding means to receive a cap, of means for engaging under the cap for holding same in the gripping means when same is in cooperative relation with the feeding means.

5. In a machine for applying threaded caps, a cap applying device including contractable cap gripping means adapted normally to freely surround a cap, means for engaging the cap to hold same freely within the gripping means, means for causing relative movement of a container and said gripping means to establish initial cap applying relation therebetween, and means operable upon the establishment of said cap applying relation for applying said gripping means, wherein said cap holding means includes a group of circularly arranged cap engaging fingers mounted rotatably around said gripping means.

45. 6. In a machine for applying threaded caps, a cap applying device including contractable cap gripping means adapted normally to freely surround a cap, means for engaging the cap to hold same freely within the gripping means, means for causing relative movement of a container and said gripping means to establish initial cap applying relation therebetween, and means operable upon the establishment of said cap applying relation for applying said gripping means, wherein 50 said cap holding means includes a group of circularly arranged cap engaging fingers pivotally mounted about and arranged to be rotatable around said gripping means, and means for resiliently contracting the fingers.

60. 7. In a machine for applying threaded caps, a cap applying device including cap gripping means adapted normally to loosely surround a cap, means for engaging the cap to hold same within the gripping means, means for causing relative movement of a container and said gripping means to establish cooperative relation therebetween, and means operable upon the establishment of said cooperative relation for applying said gripping means, wherein there is a rotating hollow 65 head within which is arranged the gripping means and wherein the cap holding means includes a group of fingers arranged about and in cooperative pivotal connection with the head and having free ends projecting under the gripping means to support the cap.

8. In a machine for applying threaded caps, a cap applying device including cap gripping means adapted normally to loosely surround a cap, means for engaging the cap to hold same within the gripping means, means for causing relative movement of a container and said gripping means to establish cooperative relation therebetween, and means operable upon the establishment of said cooperative relation for applying said gripping means, wherein there is a rotating hollow 10 head within which is arranged the gripping means, wherein the cap holding means includes a carrier member loosely mounted upon the head and a group of fingers arranged about the hollow head being pivotally mounted on the carrier and 15 having free end portions projecting under the gripping means to support the cap.

9. In a machine for applying threaded caps, a cap applying device including cap gripping means adapted normally to loosely surround a cap, means for engaging the cap to hold same within the gripping means, means for causing relative movement of a container and said gripping means to establish cooperative relation therebetween, and means operable upon the establishment of 20 said cooperative relation for applying said gripping means, wherein the gripping means includes a plurality of circularly arranged jaws, wherein the cap holding means includes a group of movable fingers in cooperative connection with the 25 jaws to project thereunder to support a cap therein, and wherein the applying means includes a ring portion surrounding the jaws, said ring and jaws arranged for limited relative axial movement and having cooperating cam formations 30 operable upon said movement for applying the jaws.

10. In a machine for applying threaded caps, a cap applying device including contractable cap gripping means adapted normally to freely surround a cap, means for engaging the cap to hold same freely within the gripping means, means for causing relative movement of a container and said gripping means to establish initial cap applying relation therebetween, and means operable 40 upon the establishment of said cap applying relation for applying said gripping means, wherein the cap holding means includes a group of annularly arranged inwardly and outwardly movable cap holding members having inner portions 45 formed to provide a tapered seat for the edge of the cap within the gripping means, and means for resiliently urging the members inwardly.

11. The combination with a machine of the class described having cap feeding means, a container support and a cap applying chuck adapted normally to loosely receive a cap, and being movable into cooperative relation with a container on the support to apply the cap thereto, of mechanism for loosely supporting the cap in the chuck 60 during said movement of same, wherein said mechanism includes a group of annularly arranged inwardly and outwardly movable cap supporting members having inner portions formed to effect movement of the members by the cap 65 upon its entry into the chuck when same is brought into cooperative relation with the feeding means and being formed to provide a tapered seat for the cap in the chuck, and means for resiliently urging the members inward.

12. In a machine of the class described, a rotating spindle, cap gripping means connected at the end of the spindle for limited axial movement with respect thereto and adapted to snugly receive a skirted cap therein, a carrier member 75

operably connected with the gripping means for axial movement therewith and rotation about the spindle axis with respect thereto, means carried by said carrier for resiliently supporting a cap in the gripping means and means operable upon 5 said axial movement of the gripping means for applying same to the cap.

13. The structure as defined in claim 12, wherein the cap supporting means includes a 10 group of resilient fingers mounted on the carrier for resiliently engaging the cap.

14. The structure as defined in claim 12, wherein the cap gripping means includes a group of annularly arranged jaws and wherein the 15 means for applying the jaws includes a cam operably connected with the spindle and cooperating to contract the jaws upon axial movement of same.

15. The structure as defined in claim 12, 20 wherein the cap supporting means includes a group of resilient fingers mounted on the carrier and having inwardly projecting ends for supporting the cap, wherein the cap gripping means includes a group of annularly arranged jaws and 25 wherein the means for applying the jaws includes a cam operably connected with the spindle and cooperating to contract the jaws upon axial movement of same.

16. In a capping head of a machine of the class 30 described, a hollow chuck head, a stem slidable within the head, a group of cap gripping jaws loosely carried on the stem, a cam surrounding the jaws and connected with the head for operating the jaws upon axial movement of the stem, 35 a carrier member mounted on the chuck head for rotatable and axial movement and being connected to move with the stem, and fingers carried by said carrier for engaging the bottom edge of a cap within the jaws.

17. In a machine of the class described, the 40 combination with a capping head having cap gripping means adapted to normally loosely receive a cap prior to applying same and having means for supporting the cap within the gripping

means, of means for operating said supporting means to effect the ejection of the cap in the event same is not applied by the head.

18. The combination with a machine of the class described, having a container support, cap feeding means, a capping head having cap gripping means adapted normally to loosely receive a cap prior to application of same and having releasable means for supporting the cap within the gripping means, said support, feeding means and head arranged for relative movement whereby cooperative relation is established between the head and feeding means for placing a cap within the gripping means, then cooperative relation is established between the support and the head for applying a cap to a container, of means for operating the supporting means prior to the establishment of cooperative relation between the head and the feeding means to effect the ejection of the cap in the event same was not applied by the head. 5 10 15 20

19. In a machine of the class described, a capping head movable to raised and lowered positions and having cap gripping means adapted normally to loosely receive a cap therein intermediate said positions and adapted to apply same when in its lowered position, releasable means for supporting a cap within the gripping means, and means operable upon the head being moved to raised position for operating the supporting means to release a cap, in the event same 25 30 35 was not applied by the head.

20. The combination with a screw capping machine having cap feeding means and cap applying means with contractable cap gripping means arranged normally to freely receive a cap therein, said gripping means and feeding means arranged for relative movement into and out of cooperative relation in feeding a cap to the gripping means, of means for engaging under the 40 cap for holding same in the gripping means when same is in cooperative relation with the feeding means.

ARTHUR I. RISSE.
